R. MACRAE

SOIL STRUCTURE

Filed July 15, 1924

Inventor:
Roderick Macrae
By Roderick Macrae Atty.

UNITED STATES PATENT OFFICE.

RODERICK MACRAE, OF CHICAGO, ILLINOIS.

SAIL STRUCTURE.

Application filed July 15, 1924. Serial No. 726,120.

To all whom it may concern:

Be it known that I, RODERICK MACRAE, a subject of the King of England, and a resident of Chicago, in the county of Cook and State of Illinois, have invented certain new and useful Improvements in Sail Structures, of which the following is a specification.

My invention relates to improved sail structures particularly adaptable for use as a propulsion source on freight vessels. My invention may be considered as an improvement over the sail construction disclosed in my Patent No. 1,304,788 of May 27, 1919.

One of the important objects of my invention is to provide interchangeable sail units from which a sail of any size can be quickly built up. Another important object is to provide an improved hoisting and supporting arrangement for the sails for eliminating the use of guide blocks or hoops on the mast so that the mast will be free for the application of stays for preventing buckling or bending under heavy service.

Another important object of the invention is to provide yards in the form of trusses preferably of steel for increasing the strength of the yards and making them very much lighter than the heavy wooden yards heretofore used.

Another important object of the invention is to so interconnect the yards of a sail structure that they may be raised or lowered independently of the sail units secured thereto and without straining such sail units.

Another object is to regularly space the yards and to have them of uniform construction and equal length so that sail units of a single size may be applied to the yards and all distortions and strains kept therefrom by the yard interconnection mechanism.

The above and other features of my invention are incorporated in the structure disclosed on the accompanying drawing of which Fig. 1 is a front elevational view of a sail structure, Fig. 2 is a side elevational view, and Fig. 3 is a sectional view on plane 3-3 Fig. 2.

On the drawing the mast M has secured to its front side a guide or traveler beam 10 which may be of T-shaped cross section as shown and which may be secured by means of screws or bolts 11. The yards are in the form of trusses T and as shown may comprise side bars or tubes 12 and 13 with connecting lattice work 14, and these trusses

are therefore very light yet of great strength. At its center each truss has secured to the inner side bar a fitting 15 having a pivot tongue 16 for engaging in the bifurcated end 17 of the slide fitting 18, pivot connections 60 being provided by bolts or pins 19. The slide fittings have the deflected ends 20 which receive the outer flanges of the traveler beam 10 and thus the slide fittings are anchored to the beam but are free to slide vertically thereon to guide the vertical movement of the yards while at the same time the yards are free to swing in horizontal planes about the pivot pins 19. The yards are spaced the proper distance apart in 70 parallel relationship by chain lengths 21 and 22 engaging between the outer and inner side bars of the various yard trusses, and to adjust the length of the chains turn buckles 23 may be inserted. These chain links of 75 which two vertical rows are shown are positioned with reference to the center of gravity of the trusses to best support them and relieve them of strains.

Secured to the mast above the sail structure is a fitting 24 supporting a sheave 25 around which travels the cable 26 which at its upper end is secured by branches 27 to the upper yard truss preferably at the upper ends of the vertical chain rows, and by 85 means of this cable the sail structure can be raised or lowered. On the drawing I have shown the cable adapted for manual operation and have shown a cleat 28 for fastening the cable after adjustment, it being understood however that an arrangement could be used for the raising or lowering of the sail structure as shown in my patent above referred to where electric motors are used. In my improved arrangement the sail unit 90 supporting structure is raised or lowered independently of the sail units 29 which I have shown to be of rectangular shape and secured at their upper and lower edges to the inner bars of the yard trusses by means of marlin ropes 30, or otherwise. Sufficient slack is allowed in the sail units to give 95 them the proper tenseness during sailing but to relieve them of all other strain and to permit the chain links in the yard trusses to assume the support of the yards. The sail units will then always retain their proper shape and will not be distorted. The units being of uniform size are readily inter-

changeable.

110

The lowermost truss T' is secured to a supporting fitting 31 which extends from a hub 32, this hub receiving and being rotatable on the mast but being held against vertical movement by the collars 33 and 34 secured to the mast. The hub supports a sprocket wheel 35 with which connection can be made by chain or belt 36 with a suitable driving source. I have shown manual means for turning the sprocket wheel 35 comprising a standard 37 supporting a sprocket pinion 38 which receives the belt 36 and is rotatable by means of a crank 39. It is understood however that motor operated driving means can be provided as disclosed in my patent above referred to. The sail structure is raised by means of the cable 26, the yard trusses above the lowermost truss then assuming their respective horizontal positions with the chain lengths taut, and the sail units will then provide the necessary sail area. By turning the sprocket wheel 35 the lower yard will turn with the hub 32 and the upper yards will swing on the pivots 19 so that the sail structure can set for tacking or other sailing conditions.

By my improved arrangement hoops or other guide blocks for traveling along the mast are eliminated and consequently the mast is free for the application of stay cables 40 for securely anchoring the mast and preventing buckling thereof. The traveler beam 11 which is preferably of steel will also add great strength to the mast and permit a much lighter mast to be used.

When it is desired to furl the sail the cable 26 is slackened sufficiently to permit any number of the yard trusses to be secured together, the rectangular sail units then readily folding themselves in flat condition between the trusses. When the entire sail structure is lowered the trusses will lay in a vertical row on the lowermost truss and it will be impossible for the sail units to become tangled but they will readily unfurl when the said structure is again raised. The sides of the sail structure can also be readily increased by adding yard trusses and sail units. The tension of the sail units can be adjusted for by means of the turn buckle 23 so that they will always produce the most efficient sailing conditions.

I thus produce a light, strong, and efficient sail structure which can be quickly, readily and accurately manipulated during sailing and in which the sail units are subjected to no strains or distortions and are required to resist only the wind pressure. By means of my improved sail structure lighter and stronger mast structure will result which can be efficiently stayed against buckling. I do not desire to be limited to the exact construction arrangement and operation shown and described as modifications can be made

which will still come within the scope of the invention.

I claim as follows:

1. In sail structures of the class described, the combination of a mast, a traveler beam secured thereto, supporting fittings anchored to but adapted to slide longitudinally along said traveler beam, yards pivoted to said fittings to swing in horizontal planes, sail units secured to and between said yards to form sail surface, and means for raising and lowering said yards. 70
75

2. In sail structures of the class described, the combination of a mast, a traveler beam secured to said mast, fittings adapted to slide along said beam, yards pivoted to said fittings, and a sail secured to said yards. 80

3. In sail structures of the class described, the combination of a mast, a traveler beam secured to said mast and having retaining flanges, fittings retained by said flanges to said beams but adapted to travel longitudinally thereon, yards secured to said fittings, sail units between said yards and secured thereto, and means for raising and lowering said yards. 85
90

4. In sail structures of the class described, the combination of a mast, a traveler beam secured to said mast and having retaining flanges, fittings retained by said flanges but free to travel longitudinally along said beams, yards pivoted to said fittings to swing in horizontal planes, sail units extending between and secured to said yards, tension lengths between said yards for taking the weight thereof from said sail units, and means for raising and lowering said fittings and thereby said yards to spread or lower said sail units. 95
100

5. In sail structures of the class described, the combination of a mast, a traveler beam secured thereto, fittings retained on said beams but free to travel longitudinally thereon, yard structures pivoted to said fittings to swing in horizontal planes, a lower yard structure, a fitting pivoting said lower yard structure to said mast to rotate thereon, sail units between said yard structures, means for raising and lowering the yard structures above said lower yard structure, and means for swinging said lower yard structure and with it the other yard structures. 105
110
115

6. In sail structures of the class described, the combination of a mast, a traveler beam secured to said mast, fittings retained on said beams but free to travel longitudinally thereon, yard structures in the form of trusses secured to said fittings, sail units between said yard structures, and means for raising and lowering said yard structures. 120
125

7. In sail structures of the class described, the combination of a mast, a fitting rotatable on the lower end of said mast but restrained against vertical movement, a lower yard structure supportable by said fitting, a 130

traveler beam secured to the mast above said lower yard structure, fittings on said beam free to travel longitudinally thereon, yard structures pivoted to said beam fittings to

5 slide therewith, sail units between said yard structures, means for turning said lower yard structure supporting fitting whereby to turn said lower yard structure supporting fitting whereby to turn said lower yard 10 structure and to swing the other yard structures, and means for raising and lowering the yard structures above said lower yard structure.

8. In sail structures the combination of a 15 mast, a lower yard structure, means restraining said yard structure against vertical movement but for adapting it for horizontal swing, a traveler beam secured to said mast above said lower yard structure, fittings slideable along said traveler beams, upper yard structures pivoted to said fittings to swing in horizontal planes, sail units between said yard structures, means for swinging said lower yard structure and thereby said upper 20 yard structures, and means for raising and lowering said upper yard structures.

9. In sail structures, the combination of

a mast, a traveler beam secured to said mast, fitting slideable along said beam, yards in the form of steel trusses pivoted to said fittings, 30 and sail units between said yards.

10. In sail structures of the class described, the combination of a mast structure, yards in the form of trusses comprising front and rear bars and interconnecting lattice work, means on each yard for connecting its rear bar for sliding engagement with said mast, cables connecting the front bars and the rear bars of the several yards for supporting them, sail units between said 40 yards, and means for raising and lowering said yards.

11. In sail construction, the combination of a mast, yard structures supported to slide along said mast and to rotate horizontally 45 relative thereto, sail units between said yards, means for raising and lowering said yards, and means for rotating said yards, each yard being in the form of a truss comprising front and rear bars and interconnecting lattice work.

In witness whereof, I hereunto subscribe my name this 10th day of July, A. D., 1924.

RODERICK MACRAE.
